UNITED STATES PATENT OFFICE

157,323

HELICOPTER

Charles Arthur Barnett, West Chester, Pa., assignor to Kellett Aircraft Corporation, a corporation of Delaware

Application August 10, 1948, Serial No. 148,015

Term of patent 14 years

(Cl. D71—1)

To all whom it may concern:

Be it known that I, Charles Arthur Barnett, a citizen of the United States of America, residing in the city of West Chester, in the county of Chester and State of Pennsylvania, have invented a new, original, and ornamental Design for a Helicopter, of which the following is a specification, reference being had to the accompanying drawings, forming a part thereof.

Fig. 1 is a front perspective view of the helicopter embodying the new design, portions of the propeller blades being broken away for convenience of illustration;

Fig. 2 is a top plan view;

Fig. 3 is a front elevational view; and

Fig. 4 is a rear elevational view thereof.

I claim:

The ornamental design for a helicopter, substantially as shown.

CHARLES ARTHUR BARNETT.
